UNITED STATES PATENT OFFICE.

GUSTAV GENZLINGER, OF HUNTINGDON VALLEY, PENNSYLVANIA, ASSIGNOR TO
FRANKLIN RAILWAY SUPPLY COMPANY, OF NEW YORK, N. Y., A CORPORATION
OF DELAWARE.

TRUCK-CENTERING DEVICE.

Application filed October 5, 1927. Serial No. 224,045.

My invention relates to an improved truck centering device which is primarily intended for use on locomotive trucks, but is also applicable to other trucks, such, for example, 5 as railway car trucks. The type of truck with which my invention has to do is commonly known as a "lateral motion" truck.

One of the objects of my invention is the provision of an effective centering device 10 for trucks of the character described which not only has extended life, but which is of such character that the possibility of breakage and failure is practically eliminated.

How the foregoing, together with such 15 other objects and advantages as may herein-after appear, or are incident to my invention, are realized, is illustrated in preferred form in the accompanying drawings, wherein—

Fig. 1 is a fragmentary sectional view 20 through a truck such as commonly used in railway practice to which my device is applied, the section being taken through the central portion of the truck and my improved centering device and certain other parts appearing in elevation.

Fig. 2 is a fragmentary section taken on the line 2—2 of Fig. 1.

Fig. 3 is a fragmentary view illustrating a 30 modification of my invention.

Fig. 4 is a perspective view of a modified detail of my invention.

Fig. 5 is a face view of a modified rocker 40 to be associated with the detail shown in Fig. 4, and

Fig. 6 illustrates still another modification 45 of my invention.

Referring now more particularly to Figs. 1 and 2, the reference letter A indicates the main frame of a truck constructed in a manner 50 common in railway practice, B indicates a center plate, and C indicates a center pin which is received by the center plate B.

The center plate B is provided with a pair 55 of spaced members 7, 7 which rest upon the upper point or surface of the pairs of rocker members 8, 8. These rocker members are provided with spaced trunnions 9, 9 which seat in the correspondingly spaced seats or rounded grooves 10, 10. In this instance I 60 have shown the seats 10, 10 as being formed in the detachable strips 11 which may be secured in any suitable manner to the support or cross member 12 connecting the side members of the truck frame. Although this is

a preferred construction it will be understood 55 that the seats may be formed directly in the support if desired.

The rockers 8, 8 each comprise a pair of spaced substantially heart-shaped members connected by means of the member 13, in 60 this instance shown as integral therewith. The usual link mechanism D may be provided.

As thus far described the construction of 65 the device is similar to centering devices now used, and further description of these parts is not deemed necessary.

Referring now to my improvements, I propose to extend the life of such devices and to make such devices more effective by providing means adapted to take some of the thrusts developed in operation of the device and thus relieve the trunnions 9 of much strain and also very materially reduce wear of the trunnions as well as of their seats. To 70 the accomplishment of these ends I have provided trunnion-like means E for the rocker devices in addition to the usual trunnions 9, 9. In the form illustrated in Figs. 1 and 2 I have provided upstanding tooth shaped 75 members 14 on the plates 11 which are located intermediate the spaced rocker seats 10, 10. Each member 14 has a curved surface 15 struck from a center coinciding with the axis of the trunnion seat as indicated by the radial line 15^a and a curved surface 16 struck from a center coinciding with the axis of the other trunnion and seat as indicated by the radial line 16^a. The rockers are provided with recesses or grooves 17 having curved surfaces 80 correspondingly struck which contact with the curved surfaces of the members 14. Stated in another way the surface 15 is curved concentrically with one of the trunnions 9 and the surface 16 is curved concentrically 85 with the other trunnion 9.

Assuming now that lateral motion takes place in a direction to cause the rockers to swing about the right hand trunnions 9, it will be noted that the left hand curved surfaces of the grooves 17 slide on the curved surfaces 15 of the members 14, thus providing bearing surfaces in addition to the trunnion bearing surfaces. When the rocker 90 swings in the other direction the additional bearing surfaces are provided by the opposite curved surfaces. The provision of these 95 extra bearing surfaces very materially re-

- duces the wear at the trunnions 9 for the reason that all of the thrusts developed in operation of the device, i. e., when lateral motion occurs, do not have to be taken at the trunnions 9 alone, but are taken in part by the trunnion means E. In other words, each rocker is, in fact, provided with three trunnion-like means, at least two of which are adapted to take thrusts during operation of the device. Through the practice of my invention the possibility of breakage at the trunnions is practically eliminated as is also the tendency for the trunnions 9 and their seats to wear out of shape.
- 15 It is to be noted that when the device is in its normal position, as illustrated in Fig. 1, the trunnion-like means E serve to relieve the trunnions 9 of wear which would otherwise occur due to the pounding of the truck over rough tracks.

In the modification illustrated in Fig. 3 I have shown the tooth-like member 14^a as being formed on the rocker 8^a and the groove 17^a as being formed in the seat plate 11^a.

- 20 Fig. 4 illustrates a seat plate 11^b which is used in association with a rocker 8^b illustrated in Fig. 5, the plate 11^b being provided with a half tooth-like member 14^b and a half groove 17^b and the rocker being provided with a half groove 17^c adapted to cooperate with the member 14^b and a half tooth-like member 14^c adapted to cooperate with the groove 17^b. The rockers and supports illustrated in Figs. 4 and 5 combine the improved features of 35 the form shown in Fig. 1 and the form shown in Fig. 3.

In Fig. 6 I have provided a machined surface 14^d at the top of the member 14 and a machined surface 14^e on the rocker at the bottom of the groove, which surfaces are adapted to abut when the rocker is in its normal position as illustrated. This further ensures against distortion or wear of the trunnions 9 when the truck pounds in traversing rough 45 tracks.

I claim:—

1. In a centering device for railway vehicles, the combination of rockers having trunnions thereon, supporting seats for said trunnions, and supplemental bearing surfaces cooperating to take a portion of the thrusts developed in operation of the device.
2. In a centering device for railway vehicles, the combination of rockers having trunnions thereon, a support having seats for said trunnions, and supplemental means taking a portion of the thrusts developed in operation of the device including cooperating bearing surfaces on the rockers and support.
3. In a centering device for railway vehicles, the combination of rockers having trunnions thereon, a support having seats for said trunnions, and supplemental means taking a portion of the thrusts developed in operation of the device including curved surfaces

on the rockers and curved surfaces on the support, said surfaces cooperating to constitute seats for the rocker supplementing the aforesaid seats.

4. In a centering device for railway vehicles, the combination of rockers having spaced trunnions thereon, a support for the rocker having spaced seats for the trunnions, and bearing surfaces on said support intermediate the spaced seats engageable by the 75 rocker and taking thrusts developed in operation of the device.

5. In a centering device for railway vehicles, the combination of a rocker having trunnions thereon, a support having seats for 80 said trunnions, a tooth-like member on said support, and a recess in said rocker complementary to the tooth-like member.

6. In a centering device for railway vehicles, the combination of a rocker having 85 spaced trunnions thereon and a support having correspondingly spaced seats for said trunnions, said rocker having curved surfaces struck from centers coinciding with the axes of the trunnions, and said support having 90 curved surfaces struck from centers coinciding with the axes of the seats, the curved surfaces on the rocker being so disposed with relation to the curved surfaces on the support that bearings in addition to those afforded by the seats are provided for the 95 rocker.

7. In a centering device for railway vehicles, the combination of a rocker member having spaced trunnions thereon and a support member having correspondingly spaced 100 seats for said trunnions, said rocker member having curved surfaces concentric with the trunnions, and said support member having curved surfaces concentric with the seats, a 105 curved surface of one of said members bearing on a curved surface of the other of said members.

8. In a centering device for railway vehicles, the combination of a rocker, a support, 110 more than two trunnion-like means, and seat means cooperating with the trunnion means whereby thrusts in the operation of the device are taken by at least two of the trunnions.

9. In a centering device for railway vehicles, the combination of a rocker, a support, 115 more than two trunnion-like means, and seat means cooperating with the trunnion means whereby thrusts in the operation of the device are taken by at least two of the trunnions, together with abutment means for relieving said trunnions of undue vertical thrusts when the rocker is in normal position.

10. In a truck centering device the combination of rocker means, bearings upon which 120 said rocker means may rotate when displaced laterally and supplemental bearings for taking a portion of the thrusts developed in operation of the device.

11. In a truck centering device the com- 125

bination of a rocker member, a bearing member, one of said members having spaced trunnions and the other spaced seats for the trunnions and said members having cooperating bearing surfaces adapted to supplement the trunnions and seats in taking thrusts developed in operation of the device.

12. A rocker for truck bearings having

spaced trunnions and curved bearing surface intermediate the trunnions, said surfaces being struck from centers coinciding with the axes of the trunnions.

In testimony whereof I have hereunto signed my name.

GUSTAV GENZLINGER.
